ELECTRICAL DISPLACEMENT-RESISTANCE CONTACT MEMBER AND METHOD OF MANUFACTURE THEREOF

Harold C. Pasini, Fair Lawn, N. J., and George M. Heckel, Elmhurst, N. Y., assignors to Fairchild Camera and Instrument Corporation, a corporation of Delaware

Application October 14, 1944, Serial No. 558,720

6 Claims. (Cl. 201—62)

1

This invention relates to electrical contacts for resistors and to the method of their manufacture and, while it is of general application, it is particularly useful in a system for winding precision resistors including circuit means for continuously comparing the resistor being wound with a variable portion of a reference resistor, together with means for controlling the winding of the precision resistor by such circuit means, and the invention will be described as embodied in such a system.

In various electrical systems it is frequently desirable to procure, in response to a given displacement of an element, a resistance value which is continuously variable in accordance with an accurately predetermined displacement-resistance characteristic over the extent of such displacement. In general this presents a problem, even when a linear displacement-resistance characteristic is desired, as resistors with accurate linear displacement-resistance characteristics often are not economically feasible. In installations in which non-linear displacement-resistance characteristics are desired, the problem is more difficult and in general requires some non-linear driving mechanism, such as a mechanical cam, interposed between the movable elements and the adjustable resistor. Not only is the accurate construction of such a mechanical cam costly but in some cases the steepness of the required displacement-resistance characteristic involves excessive cam pressure angles which limit the sensitivity and accuracy of the system of which the cam forms a part.

It is an object of the invention, therefore, to provide a new and improved electrical contact for resistors by means of which any desired displacement-resistance characteristic may be obtained, at the same time obviating the limitation of the prior art arrangements for procuring similar results.

It is another object of the invention to provide a new and improved electrical contact for resistors by means of which any desired displacement-resistance characteristic may be obtained and one which is simple and economical in construction and accurate and sensitive in operation.

It is a further object of the invention to provide a new method of manufacture of electrical contacts for resistors of the type described.

In accordance with the invention, an electrical contact for a resistor having a predetermined displacement-resistance characteristic comprises a thin deformable electrically conductive metallic member having a linear-developed surface and a lineal relief portion indented thereon. The

relief portion has a configuration related to the displacement-resistance characteristic of the resistor. By the term "linear-developed surface" as used herein and in the appended claims is meant a regular surface developed by a given line moving around or along a given generating path, well known examples being plane surfaces and circular cylindrical surfaces.

Further in accordance with the invention, the method of manufacturing a displacement-resistance contact member of the type described from a sheet of conductive material comprises producing on one surface of said sheet a graph of the desired displacement-resistance characteristic, disposing a wire along said graph, and rolling the sheet and wire to cause the wire to emboss a relief portion on the opposite surface of the sheet.

Further in accordance with the invention, an electrical contact member of the type described is embodied in a system for winding precision resistors including circuit means for continuously comparing the resistor being wound with a variable portion of an elongated reference resistor and means for controlling the winding of the precision resistor by such circuit means, the electrical contact member being provided for including a variable portion of the reference resistor in the circuit means.

For a better understanding of the invention, together with other and further objects thereof, reference is had to the following description taken in connection with the accompanying drawings while its scope will be pointed out in the appended claims.

Referring now to the drawings, Fig. 1 is a graph illustrating a type of displacement-resistance characteristic which may be desired; Fig. 2 is a top view of an electrical contact member to which the characteristic of Fig. 1 is transposed; Fig. 3 is a circuit diagram, partly schematic, of a complete system for winding precision resistors with any desired displacement-resistance characteristic and embodying the electrical contact of the invention; while Figs. 4a and 4b are side and end views, respectively, of a modified form of electrical contact member involving a rotational rather than a translatory displacement.

Referring now to the drawings, there is represented an electrical contact member for deriving from a reference resistor in response to a given displacement a continuously variable resistance value having a predetermined displacement-resistance characteristic, as represented by a continuously variable portion of the reference resistor, together with a system for winding pre-

cision resistors in which such electrical cam is utilized. It is assumed that it is desired to obtain a displacement-resistance characteristic of a predetermined shape. This characteristic is first plotted on appropriate coordinate paper, as represented in Fig. 1, in which the abscissas represent the percentage of length of the resistor, that is, of the given displacement, and the ordinates represent the percentage of maximum resistance. The characteristic of Fig. 1 is then reproduced on a conductive metallic member or template having a linear developed surface, such as the plane surface of member 9 of Fig. 2. The characteristic of Fig. 1 may be transferred to the template of Fig. 2 by photo-engraving, or like photographic process, by manually depositing a fine and uniform ridge of conductive material thereon, by embossing, or by any other equivalent process. Preferably the member 9 is a thin sheet or a thick foil of conductive material such as aluminum and the desired characteristic is transferred to one surface thereof by tracing the curve of Fig. 1 thereon with carbon paper. Thereafter a fine wire, for example No. 18 gauge, is disposed along the traced characteristic and, adhesively retained in place, as by an adhesive tape. This sheet is then run through a pair of rollers, the roller engaging the wire side of the member 9 being rigid and the other being semi-resilient, such as hard rubber, so that the wire indents or embosses a relief portion on the opposite surface of the member 9. In any event, there is developed on member 9 a relief portion 9a, preferably lineal as illustrated, which has a configuration which is a reproduction of the characteristic of Fig. 1.

The member 9 of Fig. 2 can then be utilized in a system for winding precision resistors such as represented in Fig. 3, which is of the same general type as described and claimed in the copending application of Henry E. Hale, entitled Method of and apparatus for winding precision resistors and resistors formed thereby, Serial No. 514,894, filed December 20, 1943. This system includes circuit means for continuously comparing the resistor being wound with a variable portion of an elongated reference resistor and means for controlling the winding of the precision resistor by such circuit means. Specifically, the system of Fig. 3 comprises a winding mechanism consisting of a pair of holders 10 and 11 supported in bearings 12 and 13, respectively, adapted resiliently to hold an elongated resistor card 14 of insulation material, the holder 11 being biased into engagement with the card 14 by means of a spring 15. A manually operable knob 16 is provided for initiating a few turns on the card 14. The winding mechanism also includes means for winding resistance wire on the card 14 to form a resistor R and consisting of a feed-wire holder 17 in which is mounted a spool 18 carrying a supply of resistance wire 19, the wire being passed through a guide and tensioning element 20 constituting an extension of the holder 17. The wire after passing through the element 20 is fed to the resistor card 14 in a conventional manner to form a resistor thereon. The card 14 is adapted to be rotated at constant speed by means of a suitable motor 21 and reduction gearing 22. Electrical connections are made to the resistor R during winding by means of a sliding contact 20a attached to guide 20 and bearing on the wire 19 as it is fed to card 14 and a brush 11a bearing on the conductive holder 11 which is connected to a terminal 14a on card 14 or to any other suitable connection to the start-

ing point of the winding forming the final resistor R.

The winding apparatus also includes an advancing means for producing relative transverse movement between the resistor card 14 and the feed-wire holder 17 during rotation of the card 14 to form a resistor thereon. This advancing means comprises a feed screw 23 engaging a threaded portion 11a of the holder 17 and driven by a follow-up motor 24 through reduction gearing 25. The feed screw 23 is journaled in supports 26, 26 which also hold a guide rod 27 engaging an extension 17b of the holder 17 to maintain steady transverse movement of the holder 17. In order to impart to the resistor R, formed as described, a displacement-resistance characteristic which is an accurate reproduction of that of Fig. 1 and of the relief portion 9a of member 9, the system comprises means including the electrical contact of the invention for continuously comparing the resistance value of the resistor R during the winding operation with that of a corresponding variable portion of a reference standard resistor. Specifically, a reference standard resistor 30 is mounted in a yoke 31, including guide ways 31a sliding on a pair of guides 32 supported in a frame 33. The yoke 31 also includes a threaded nut 31b engaging a threaded rod 34 comprising an extension of a shaft 34a journaled in the frame 33. The frame 31 is disposed to slide the reference resistor 30 over the member 9 maintaining a continuous contact between the resistor 30 and the relief portion 9a of the member 9, the frame 31 and its operating mechanism thus comprising means for producing relative translatory motion between the member 9 and the resistor 30.

The system of Fig. 3 also includes a pair of output terminals comprising the terminal 9b connected to the relief portion 9a of the member 9, which connection, in case of homogeneous metallic construction, may constitute a connection to any point of the member 9, and the terminal 31c connected to an adjustable contact 31d engaging a conductive portion of the frame 31 in electrical connection with a fixed point on the reference resistor 30, preferably the end or zero point of the resistor. The portion of the resistor wound on the card 14 at any moment is compared with the portion of the reference resistor 30 included between terminals 9b and 31c by means of an electrical bridge including as two adjacent arms the corresponding portions of the reference resistor 30 and the resistor R and as the other two arms resistor elements 35 and 36 of predetermined relative resistance values, the bridge being connected to compare such portions of resistors 14 and 30 by electrically balancing them against each other in the bridge circuit. To this end, one secondary winding 37 of a supply transformer 38 is connected across one diagonal of the bridge circuit described, while the other diagonal of the bridge circuit is connected to the input circuit of a servo-amplifier unit 39. The power supply circuit of the amplifier unit 39 is energized from a secondary winding 41 of the supply transformer 38, while the output circuit of the amplifier 39 is connected to energize the follow-up motor 24 which produces a relative transverse movement between the wire-feed apparatus and the resistor card 14.

In order to effect movement of the resistor 30 over the relief portion 9a of the member 9, corresponding to the given range of displacement of the yoke 31, for selecting a continuously vari-

able portion of the reference resistor, the yoke 31 is driven synchronously with the wire-feed holder 17 by means of the motor 24, the gearing 25, bevel gearing 42 and 43 and the threaded shaft 34 engaging the nut 31b of the yoke 31.

The motor 21 is energized from a secondary winding 44 of transformer 38 while a switch 45 is included in the primary circuit of the transformer 38 to effect simultaneous energization and de-energization of the several circuits of the apparatus to start and stop the winding operation. If desired, suitable automatic stopping devices well known in the art may be included automatically to stop the system upon the completion of winding of any resistor R.

Referring now to the operation of the system of Fig. 3 described above, it will be assumed that the resistor card 14 is placed in the holder and a few turns wound thereon by means of the manually actuated knob 16 until the wire reaches the terminal 14a or other equivalent connection to the starting point of the winding. It is assumed that, at this point, the adjustable yoke 31 is at the extreme left-hand limit of its movement, in which position all of the resistor 30 is cut out of the bridge circuit. Assuming that at this point there is a small amount of resistance, which may be inherent circuit resistance with or without an added resistance element approximately to balance the bridge circuit under these conditions and which is represented by dotted-line resistor R₀ in circuit with the reference resistor 30, the bridge circuit comprising elements R, R₀, 35, 36 is slightly unbalanced. The unbalance voltage is applied to the amplifier 39, is amplified therein, and applied to the follow-up motor 24, initiating transverse movement of the feed-wire holder 17 to start the formation of the resistor R on the card 14. At the same time the follow-up motor through the gearing 25, 42, 43 actuates the threaded rod 34 to advance the yoke 31, which is effective to move the reference resistor 30 over the relief portion 5a of the conductive member 5 to include continuously increasing portions of the resistor 30 in the bridge circuit.

When the apparatus described has reached a state of equilibrium, there will be a substantially constant difference in resistance between the portion of the reference resistor 30 included in the bridge circuit and the portion of the resistor wound on card 14, this difference being only the small amount required to maintain the unbalance of the bridge circuit sufficient to actuate the follow-up motor 24 for advancing the feed-wire holder 17 relative to the resistor card 14. Since the card 14 is rotated at constant speed by motor 21 to wind a given number of turns per unit of time, while the wire-feed holder 17 and the yoke 31 are advanced synchronously but at a variable speed by motor 24 to maintain the bridge circuit in balance, the amount of resistance wire wound on the card 14 per unit of transverse movement of the feed-wire holder 17 is varied to control the displacement-resistance characteristic of the resistor R. The gearing 25 is preferably one of a number of interchangeable gearings to provide a different range of rates of advance of the holder 17 for each wire size used, the rate within each range being controlled as described. This arrangement causes the system to operate with a minimum unbalance signal and maximum accuracy.

The displacement-resistance characteristic of the resistor R is thus accurately predetermined by the characteristics of the reference standard

30 and the electrical contact member 5 and the reference resistor 30. The configuration of the relief portion 5a of the member 5 is so proportioned in relation to the displacement-resistance characteristic of the reference resistor 30 as to develop between the output terminals 3b, 31c the desired predetermined resistance characteristic which is duplicated in the resistor R being wound. In case the reference resistor 30 has an accurately linear displacement-resistance characteristic, the configuration of the relief portion 5a will correspond exactly to the desired displacement-resistance characteristic. However, in practice it will generally be more feasible to adopt a reference standard having a characteristic which may be either linear or non-linear but which preferably approximates that desired and then represent in Fig. 1 and transfer to the member of Fig. 2 a measured calibration curve effective to convert the actual displacement-resistance characteristic of the reference resistor 30 to the desired displacement-resistance characteristic. In any event, the displacement-resistance characteristic of the resistor R will be substantially matched to the resistance characteristic appearing at the terminals 3b, 31c, which is determined by the electrical cam comprising the reference resistor 30 and the member 5.

In Figs. 4a and 4b are represented a modified form of the electrical cam of the invention in which the conductive contact member having a linear-developed surface is, in this instance, a cylindrical conductive member 50 having a lineal relief portion 50a formed thereon. The member 50 is mounted for rotation on a suitable shaft 51 supported in bearings 52, 52 and includes an electrical connection 50b to a slip ring 53 having a cooperating brush 53a. The reference resistor 30 is held in suitable holders 54 and the mounting of the elements is such that, as the shaft 51 is rotated to produce relative rotation between the member 50 and the resistor 30, the relief portion 50a is biased into continuous contact with the reference resistor 30. The operation of the modification of Fig. 4a is in other respects similar to that described in connection with Fig. 3.

Thus, it is seen that by means of the electrical contact of the invention embodied in a resistor winding system, a resistor having a non-linear displacement-resistance characteristic of any desired taper or steepness may be readily formed without the disadvantages accompanying the use of a mechanical cam with a large pressure angle.

While there have been described what are at present considered to be the preferred embodiments of the invention, it will be apparent to those skilled in the art that various changes and modifications may be made therein without departing from the spirit or scope of the invention.

What is claimed as new is:

1. The method of manufacturing a displacement-resistance contact member of a sheet of conductive material which comprises, producing on one surface of said sheet a graph of the desired displacement-resistance characteristic, disposing a wire along said graph, and rolling said sheet and said wire to cause said wire to emboss a relief portion on the opposite surface of said sheet.
2. The method of manufacturing a displacement-resistance contact member of a sheet of conductive material which comprises, plotting a graph of the desired displacement-resistance

characteristic, transferring said graph to one surface of said sheet, disposing a wire along said transferred graph, and rolling said sheet and said wire to cause said wire to emboss a relief portion on the opposite surface of said sheet.

3. The method of manufacturing a displacement-resistance contact member of a sheet of conductive material which comprises, producing on one surface of said sheet a graph of the desired displacement - resistance characteristic, disposing a wire along said graph, adhesively retaining said wire in place on said surface, and rolling said sheet and said wire to cause said wire to emboss a relief portion on the opposite surface of said sheet.

4. In a system for winding precision resistors including circuit means for continuously comparing the resistor being wound with a variable portion of an elongated reference resistor and means for controlling the winding of said precision resistor by said circuit means, an electrical contact member for including a variable portion of said reference resistor in said circuit means comprising, a member having an integral linear-developed surface and a conductive relief portion thereon, means for producing relative motion between said member and said reference resistor while maintaining contact between said relief portion and said resistor, and output terminals connected to said relief portion and to a fixed point on said reference resistor, the configuration of said relief portion being so proportioned in relation to the displacement-resistance characteristic of said reference resistor as to develop the desired displacement-resistance characteristic between said terminals.

5. An electrical contact for a resistor having a predetermined displacement-resistance characteristic comprising a thin deformable electrically conductive metallic member having a linear-developed surface and a lineal relief portion indented thereon having a configuration related to said displacement-resistance characteristic.

6. An electrical contact for a resistor having a predetermined displacement-resistance characteristic comprising a thin deformable electrically conductive metallic member having a linear-developed surface and a lineal relief portion indented thereon having a configuration constituting a reproduction of said displacement-resistance characteristic.

HAROLD C. PASINI,
GEORGE M. HECKEL.
